UNITED STATES PATENT OFFICE

2,279,989

NEWSPAPER WRAPPER

Samuel E. Hirschberg, Chicago, Ill.

Application November 3, 1938, Serial No. 238,551

6 Claims. (Cl. 229—88)

This invention relates to a newspaper wrapper or bag, and more particularly to a water proof bag, wrapper, sack, envelope or container for receiving and protecting a newspaper, magazine or the like such as for home delivery, especially when delivered in inclement weather such as rain or snow, or left outside doors, in which case they are frequently soaked and rendered unusable.

An object of the invention is to provide a novel bag or wrapper which will protect the daily newspaper when delivered in the manner and under the conditions above set forth, but which can be readily torn open to obtain access to the paper and thrown away at a minimum of expense, thus insuring that the subscriber will at all times receive the newspaper in good, dry and readable condition.

Another object of the invention is to provide a bag or wrapper of the kind and type specified which is made of a novel, extremely simple and inexpensive blank so that it can be produced in quantities at a very low cost and which is so formed as to permit it to be readily sealed or tied at one end over the newspaper or the like after the latter is inserted in the bag or wrapper in a folded condition so as not to add an appreciable cost to the newspaper subscription or delivery thereof, in fact, so as to facilitate tossing thereof in making deliveries, without folding in the usual box formation which may be eliminated and which also embodies a tab whereby the bag may be readily torn open to permit removal of the newspaper.

Other objects and advantages will appear and be more fully brought out hereinafter, reference being had to the accompanying drawing, wherein:

Fig. 1 is a perspective view showing the wrapper in use;

Fig. 2 is a side elevation of the wrapper before the newspaper is inserted;

Fig. 3 is a longitudinal section taken on the line 3—3 of Fig. 2;

Fig. 4 is a view at right angles to Fig. 2 looking toward the left, but with the bag opened out and a newspaper therein;

Fig. 5 is a cross section taken on the line 5—5 of Fig. 4;

Fig. 6 is a plan view of a blank from which the new article of manufacture is produced; and

Fig. 7 is an enlarged detail showing the bottom end opened out to illustrate the manner of applying adhesive thereto.

Referring more particularly to the drawing,

the bag or wrapper constituting my invention is made from a comparatively rectangular section of water proof or oiled paper or other suitable water proof fibrous material, tearable Cellophane or the like, and preferably of sufficiently rippable but tough texture to prevent destruction thereof in normal use. The blanks are suitably stamped out from sheets and comprise a body composed of an elongated rectangular central portion 11 which forms one side of the bag. The other side may be suitably formed and suitably connected to the side 11 along one or more edges, but is shown provided with opposite and relatively narrow elongated integral sections or flaps 12 and 13 joined therewith along the side margins 14 and 15 of the portion 11, along which the blank is folded flat in parallel lines or planes. The flap 13 is folded over the flap 12 and the two connected at the overlapping portions in any suitable way. By way of illustration, the marginal portion constituting a narrow strip 16 at the outer edge of the portion 13 may be coated with adhesive as shown at 17 to cause the two portions to adhere. The bottom of the blank is provided with a folding extension 18, although generally speaking, when the sides 12 and 13 are folded on the side 11, the adjacent open end of the bag is merely folded on itself and may be secured by suitable adhesive 19 although other suitable form of connecting or fastening means may be employed. As illustrated, this adhesive is preferably disposed on the inner face of the portion 18 and both the inner and outer faces of the end portions 20 which, in the preferred embodiment, are preferably tapered or beveled toward the outer edges of the portions 12 and 13 at the end of the blank as above pointed out. This produces a flap at the bottom of the bag which is folded along the line 21, the portions 20 being secured to the portion 18 and then the two being folded over against the outsides of the portions 12 and 13 forming the other side of the bag or wrapper in addition to the side 11.

It is of course understood that the device may be economically produced in large quantities by suitable machines or otherwise and when produced, will be flat as shown in Fig. 3, although the thickness is accentuated in this view for purposes of illustration.

The opposite or top end of the bag or wrapper is provided with narrowed end portions or extensions, one extension 22 being formed at the end of the part 11 and tapering as shown. While the opposite sides are shown concaved at 23, it is to be understood that I do not desire to be lim-

ited to this formation. Opposing the tapered end or extension 22 is another tapered end or extension formed at the ends of the portions 12 and 13, as shown at 24 and 25, respectively. These portions are of course secured together in overlapping relation along the marginal portions as previously explained and these two tapered sides or ends are more than half as long as the body so that they can be readily tied together as indicated at 26 in Fig. 1 of the drawing and drawn as tight as desired over the end of the newspaper or the like 27 inserted in the bag so as to thoroughly protect the latter from becoming wet or otherwise soiled and unusable. While the bag is made to accommodate a single paper, it is of course to be understood that no limitation in this direction is desired. However, it will be noted that the bag will expand somewhat according to the condition in which the newspaper or the like is folded or rolled and will accommodate itself to the condition of the newspaper.

In order to obtain access to the newspaper within the wrapper or bag without untying the tapered end portions or tying extensions forming a closure at the open end of the bag, the latter is designed to be readily torn down the side or along one edge so that the newspaper may be removed and the bag discarded. For this purpose, the bag is formed along one edge and at the end provided with the tying extensions twisted or tied to form the knot 26 with a tab 28 extending between two of the opposed curved edges 23 of the tapered extensions of the body of the bag to which it is joined as at 29, the opposed edges diverging outwardly, if desired, as indicated at 30. However, the main aspect of this tab is to leave sufficient material at the point 29, that is, in the width of the tab so that when the tab is grasped and pulled, it will be certain to tear the bag down the side or one folded edge so that the newspaper may be removed. This device will also facilitate delivery and will especially protect the newspaper from being soiled and soaked and rendered unusable or unreadable. It may also be used for mailing purposes and will give similar protection in transit. While the special use of the device is in connection with the delivery of newspapers in doors, vestibules or porches as is common, it is to be understood that other suitable matter may be delivered therein.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent, is:

1. A protecting wrapper for newspapers for delivery purposes formed of water proof material and in the form of an elongated pocket having a

closed end and an opposite open end, and tapered tying extensions at the open end of a length greater than half the length of the pocket.

2. A protecting wrapper for newspapers for delivery purposes formed of water proof material and in the form of an elongated body formed into a pocket having a closed end, tapered tying extensions at the opposite open end more than half the length of the body, and an extension tab widened toward its free end, formed between the aforesaid tying extensions and much shorter than the same to be pulled for tearing open the wrapper.

3. A wrapper of the class described formed of a blank having a body formed of opposed sides joined along marginal edges and having a folded end forming a closed bottom and tapered extensions at the other end of a length at least half the length of the body adapted to be tied together in a knot.

4. A wrapper of the class described formed of a blank having opposed sides folded flat and joined along marginal edges and having a folded end forming a closed bottom, tapered extensions at the other end long enough to be tied together in a knot, and a tearing tab extending from the body between at least two edges of said tapered extensions for tearing open the bag along an edge, as and for the purposes set forth.

5. A wrapper for newspapers or the like for delivery purposes, comprising a blank formed of a waterproof imperforate sheet folded on itself to form a flat bag proper with relatively sharp edges and the folded portions overlapped at their edges and joined to form a tubular closure, a closed bottom for the bag, tapered extensions extending entirely across the top edges of the bag and tapering to a narrow formation with concave sides, said extensions being longer than half the length of the bag proper and adapted to be tied together and a tearing tab extending from the body and overlying at least one fold between a pair of extensions.

6. A wrapper for newspapers or the like for delivery purposes comprising a sheet of waterproof fibrous material and sufficiently rippable but tough texture to prevent destruction thereof in normal use, said sheet comprising a body having an elongated rectangular central portion and relatively narrow elongated integral flaps along the long edges thereof folded in overlapped relation against the body and secured together, the bottom edge of the sheet having a narrow extension folded against the flaps to close said end and the opposite ends of the central portion and flaps having tapered extensions, the extensions of the flaps being disposed in overlapped relation along their edges and secured together, said extensions adapted to be tied to close said end, and a tab projecting from one end of the sheet between a pair of extensions in alignment with the folding line of a flap to tear open the wrapper along said line.

SAMUEL E. HIRSCHBERG.
